(57) **CLAIM**

The ornamental design for a tower humidifier, as shown and described.

DESCRIPTION

FIG. 1 is a front perspective view of a tower humidifier showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross sectional view taken along line 8—8 of FIG. 7, where in the interior components, including a large compartment of a water reservoir located near the top of the humidifier, a small compartment of the water reservoir, an ultraviolet lamp coupled to the small compartment of the water reservoir, a water tray, a cylindrical filter, and a rotary fan, are all shown in broken lines for illustrative purposes only and do not constitute a part of the claimed design; and,

FIG. 9 is a perspective view thereof, wherein some of the interior components, including a portion of the large compartment of the water reservoir located near the top of the humidifier, the small compartment of the water reservoir, an ultraviolet lamp coupled to the small compartment of the water reservoir, the water tray, and the cylindrical filter, are shown in broken lines for illustrative purposes only and do not constitute a part of the claimed design.
